UNITED STATES PATENT OFFICE.

GEORGE MARVIN SAVAGE, OF LOS ANGELES, CALIFORNIA.

WELL SHUT-OFF.

1,170,851.

Specification of Letters Patent.

Patented Feb. 8, 1916.

Application filed December 14, 1914. Serial No. 877,085.

To all whom it may concern:

Be it known that I, GEORGE MARVIN SAVAGE, a citizen of the United States, residing at Los Angeles, in the county of Los Angeles and State of California, have invented new and useful Improvements in Well Shut-Offs, of which the following is a specification.

This invention relates to a shut-off device for wells; particularly for oil wells and the like where fluid under great pressure is frequently encountered; and the invention consists in the provision of an effective and easily operated provision for controlling the flow of fluid from a well flowing under great pressure.

There are several features of my invention which I wish to particularly emphasize; prime among which are the construction and form of the cap members which are forced over the upper end of the casing and the means connected with these cap members for controlling the flow of fluid, and also the means for mounting and moving the cap members. These features will be best understood from the following specification and the accompanying drawings, wherein I describe and illustrate a preferred form of my device.

In the accompanying drawings, Figure 1 is a vertical section showing my improved well shut-off in use and Fig. 2 is a horizontal section taken as indicated by line 2—2 of Fig. 1.

In the drawings the well casing is illustrated as 10 and the floor of the derrick about the well is illustrated at 11. The casing may be supported in any well known manner as by a spider 12 mounted upon a suitable foundation or support 13 beneath the derrick floor; it being essential to the use of my invention that the upper end of the casing be supported approximately at a fixed point, so that the shut-off mechanism will register with the casing. The shut-off mechanism is permanently mounted beneath the derrick floor ready for use at any time; and being so permanently mounted, after the well starts to flow it is only necessary to perform the simple operation of moving the heads of the casing caps toward each other over the casing as will be hereinafter described.

In the preferred form of my shut-off mechanism I employ a number of an-

chor piers 14 arranged on opposite sides of the well casing; and at the upper ends of these piers there are carried two opposite horizontal beams 15, secured to the piers in any suitable manner at a convenient height above the ground. These piers and beams are of suitably heavy construction to withstand the upward pressure of the fluid flowing through the casing.

Transverse guide rods 20 are mounted between the opposite beams 15, these rods forming the transverse ways on which the opposite halves 21 of the casing caps are adapted to slide. In the preferred form I provide four of these transverse bearing rods 20 of suitable size and strength to withstand the upward pressure on the casing cap. The casing cap, as hereinbefore stated, is preferably formed in halves, each half having a semi-cylindrical piece 25 for reception of the upper end of the casing 10. When the halves are forced together, these pieces fit tightly around the upper end of the casing. Immediately above the upper end of the casing there are passages 26 in each cap half, which passages lead to outlets 27 each controlled by a separate valve 28. The number of outlets in each cap half may be varied; but I prefer to provide two opposite outlets in each cap half, each controlled by a valve 28; so that there are four separate outlets from the cap. Each of these outlets is of a size nearly or quite equal to the size of the casing; so that the fluid, after it emerges from the upper end of the casing, is afforded an easy and free outlet from the cap. Pipes 30 may or may not be permanently connected with the valves 28 as indicated for one of the valves in Fig. 2.

During drilling operations the cap halves are moved apart from each other away from their positions over the upper end of the casing. The upper end of the casing is thus left free and open for drilling operations. When it is desired to shut off the flow of fluid from the upper end of the casing, the cap halves are moved inwardly through the medium of the heavy screws 35. These screws 35 are mounted in suitable bearing nuts 36 on the beams 15 and press with their inner ends against the cap halves 21. The outer ends of the screws may be arranged for application of a wrench; or the screws may be operated in any convenient or suitable manner. For instance, connec-

tion may be made with the screws for operation from a distance, if desired.

In the operation of my well shut-off, the complete installation is made before or while 5 the well is being drilled; so that the complete apparatus is ready for instantaneous use should the well begin to flow under pressure. When this occurs, the screws 35 are operated to screw the cap halves toward 10 each other over the end of the casing, to the position shown in the drawing. During this operation the valves 28 are all wide open, so as to allow free exit for the fluid through the valve controlled outlets. The 15 pipes 30 may be all ready attached to the valves for leading the fluid some way off. If these pipes are not already attached, it is only necessary to then shut off one valve, at a time and to attach one pipe at a time, 20 immediately afterward opening the closed valve to allow the exit of fluid through its pipe. Thus, in attaching the pipe to lead the fluid to a distant point it is only necessary to close off one of the outlets at any 25 time; and by this mode of operation the full fluid pressure is never confined within the cap and the cap is not subjected to the maximum pressure. The outlets are of such aggregate capacity that any one of them 30 may be shut off at any time, and the flow of fluid may be thus directed as desired, without materially increasing the pressure upon the cap.

Another mode of operation may be carried 35 out if the apparatus is not ready when the well begins to flow; the piers may be placed, and then the beams, etc., may be placed after the well starts flowing. The beams and all the apparatus carried thereon, 40 completely set up, may be slid lengthwise between the piers on rails, skids or the like, and bolted to the piers as shown; the cap being open during the operation. The cap may then be closed and the fluid controlled 45 as before described. This may not be necessary as in some cases it will be possible to construct the apparatus right around the flowing well.

Copies of this patent may be obtained for five cents each, by addressing the "Commissioner of Patents, Washington, D. C."

Having described my invention, I claim:

1. In a well shut-off, the combination with 50 a well casing of an anchored foundation, horizontal ways thereon, a casing cap divided into halves slideable on the horizontal ways on opposite sides of the casing and having outlets, and means to force said halves together over the casing.

2. In a well shut-off, the combination with 60 a well casing of an anchored foundation, horizontal ways thereon, a casing cap divided into halves slideable on the horizontal ways on opposite sides of the casing, and means to force said halves together over the casing, said cap halves having fluid passages therein with a plurality of outlets, and valves controlling said outlets.

3. In a well shut-off, the combination with 70 a well casing of anchor piers arranged on opposite sides of the casing, horizontal beams secured to the upper ends of the anchor piers, transverse horizontal rods secured between the beams, a cap divided 75 into two halves slideable on the transverse rods on opposite sides of the casing, and means for forcing the cap halves toward each other to a position over the casing.

4. In a well shut-off, the combination with 80 a well casing of anchor piers arranged on opposite sides of the casing, horizontal beams secured to the upper ends of the anchor piers, transverse horizontal rods 85 secured between the beams, a cap divided into two halves slideable on the transverse rods on opposite sides of the casing, and means for forcing the cap halves toward each other to a position over the casing, each 85 cap half having a fluid passage with a plurality of outlets, and an individual valve controlling each outlet, substantially as and for the purpose described.

In witness that I claim the foregoing I 90 have hereunto subscribed my name this 7th day of December, 1914.

GEORGE MARVIN SAVAGE.
